UNITED STATES PATENT OFFICE

2,614,661

RAILWAY CAR WHEEL FLANGE OILER

Henry P. Fisher, Chicago, Ill.

Application October 31, 1947, Serial No. 783,385

4 Claims. (Cl. 184—3)

1

My invention relates to improvements in oilers for the flanges of wheels of railway locomotives, and the like.

An important object of the invention is to provide a wheel flange oiler for the constant supply and application of a suitable lubricant to the wheel flanges of locomotives, and the like, thus minimizing wear of flanges due to friction with the opposing surface of the rail.

A further object of the invention is to provide a flange oiler in the form of a roller which engages the wheel flange, and is self-adjusting radially and axially, with respect to the wheel.

A further object is to provide a wheel flange oiler which will use a minimum quantity of oil, while keeping the flange constantly lubricated.

A still further object of the invention is to provide a wheel flange oiler adaptable to various sizes of wheels, the oiler being simple and durable in design, and well adapted to economical manufacture.

Other objects and advantages of the invention will be apparent during the course of the following description.

In the accompanying drawings forming a part of this application, and in which like numerals are employed to designate like parts throughout the same:

Figure 1 is a side elevation of the wheel flange oiler embodying the invention and showing the same applied to the truck frame of a locomotive and engaging the flange of a wheel;

Figure 2 is an enlarged central vertical section through the flange oiler, partly in elevation, with the reservoir removed;

Figure 3 is a front elevation of the oiler with the cover plate removed, partly in vertical section;

Figure 4 is a central vertical section through the lubricating roller, with the roller removed from its supporting structure;

Figure 5 is a fragmentary side elevation of the cover plate removed;

Figure 6 is a view, partly in section and partly broken away, of the lubricant reservoir.

In the drawings, where, for the purpose of illustration, is shown a preferred embodiment of the invention, the numeral 10 designates a railway locomotive wheel forming part of a truck, including a truck frame 11. The wheel 10 includes the usual annular rail-guided flange 12, which has frictional engagement with the side surface 13 of the rail.

The oiler for lubricating the flange 12, to reduce wear due to the friction between the flange and rail, comprises a rigid plate or mounting bracket

2

14 which is rectangular and bent near its upper end to form a flat lateral extension 15 disposed horizontally in assembly, and a downwardly-inclined portion 16, Figure 1. The extension 15 has corner openings 17, receiving bolts 18, or the like, serving to rigidly secure the flange oiler to the truck frame 11. The portion 16 of bracket 14 is provided with aligned, parallel, elongated openings or slots 19 near its upper and lower corners, and these slots receive bolts 20 which extend through transverse openings 21 in an adjacent grooved plate or slide 22.

The slide 22 is adjustably secured to the bracket 14 by bolts 20, and comprises a flat rectangular plate having a central longitudinal groove 23 formed in its outer surface. The opposite sides 24 and 25 of the groove 23 diverge outwardly from corners 26 near the longitudinal center of the slide 22 and toward the upper and lower ends of slide 22. Upstanding side longitudinal portions or shoulders 27 are formed by the groove 23. An upstanding cylindrical dowel pin 28 is rigidly secured to the bottom of groove 23, and the top of the dowel pin is flush with the top or outer surfaces of shoulders 27. The dowel pin 28 is disposed at the transverse center of groove 23 and adjacent the corners 26, Figure 3.

Disposed within the groove 23 and slidable therein is an adjustable support arm or bar 29. The bar 29 is rectangular in transverse cross-section, and is provided with a center longitudinal slot 30, extending from near the upper end of bar 29 downwardly below the longitudinal center of the bar. The upstanding dowel pin 28 projects through the slot 30 and is slidable therein. The bar 29 extends for the full length of the slot 30, as shown, and below the lower ends of the slide 22 and bracket 14. The bar 29 has an enlarged head 31 at its lowermost end formed integral therewith and projecting laterally of the bar 29 at its side remote from the bracket 14. The head 31 has flat faces 32 at right angles to the bracket 14, and is provided with a transverse opening 33.

A short shaft 34 is rigidly secured to the head 31 and includes a screw-threaded extension 35 which engages in the opening 33. The shaft has an annular shoulder 36 to engage one flat face 32, and further includes an outer reduced screw-threaded extension 37, carrying a nut 38, secured in place by a cotter pin 39. The extension 35 has a nut 40 mounted thereon, and this nut serves to clamp the shoulder 36 to the head 31. A cotter pin 41 secures the nut 40 in place. The shaft 34 has a central axial bore or port 42 formed in the

end of extension 35 and terminating outwardly of the longitudinal center of the shaft. A short radial port 43 intersects the port 42 near the inner closed end of the same.

A lubricating roller 44 is freely rotatably mounted upon the shaft 34 between the shoulder 36 and nut 38. The width of roller 44 is less than the distance between the shoulder 36 and nut 38, and the roller may move axially therebetween. The roller has a large curved annular groove 45 to engage the outer curved edge of the wheel flange 12. This groove 45 forms side annular flanges 46 and 47, the flange 47 being of smaller diameter than the flange 46. The flanges 46 and 47 extend down the sides of the wheel flange 12, as shown clearly in Figure 3. The inside diameter of the roller 44 is provided with an annular groove or recess 48, which communicates with the radial port 43. The roller has four radial ports 49 equidistantly spaced angularly and leading into the annular groove 48. The ports 49 are in radial alignment and are nearer to the flange 47 than the flange 46, so as to be to the right of the lateral center of the wheel flange 12, Figure 3. Each of the radial ports 49 is countersunk at its outer end, as at 50, and an external annular oil groove 51 intersects each of the countersunk recesses 50 and is, therefore, in communication with the ports 49.

An expansible coil spring 52 is arranged in the slot 30 of bar 29 and its opposite ends engage against end pieces or keepers 53 and 54. The keeper 53 has a cylindrically-curved recess or seat 55 to engage the side of dowel pin 28. The end 56 of the keeper 54 is cylindrically curved to engage the curved end of slot 30. Longitudinally-spaced openings 57 and 58 are provided near the upper end of bar 29 for a purpose to be described. A flat rectangular cover plate 56' is mounted upon the shoulders 27 of slide 22, and serves to cover the bar 29 and associated elements. The bolts 20 project through corner openings in the cover plate and carry nuts 57'. A pair of screws 58' serve to rigidly secure the cover plate to the slide 22. A lubricating fitting 59' is mounted centrally upon the cover plate 56' and through this fitting the parts moving in groove 23 are lubricated.

The outer end of extension 35 is internally screw-threaded for a short distance inwardly, and this screw-threaded opening receives a nipple 59 carrying an elbow 60 having its outer end disposed upwardly. A section of flexible tubing 61 of any suitable material is connected to the elbow 60 and extends upwardly to a point above the roller 44, and through the bottom of a lubricant tank or oil reservoir 62. A stop-cock 63 is provided in the tubing 61 near the bottom of tank 62. The tubing 61 has a liquid-tight connection with the bottom of tank 62, as at 64. The tube 61 extends upwardly within the tank 62 near the top of the same and above the level 65 of the oil. An absorbent wick 66 extends downwardly into the oil within the tank and into the top of the tube 61, as shown. The wick 66 is secured in place by the bent cotter pin 67. The tank has a top-filling opening 68 covered by a pivoted cover 69. The tank 62 is rigidly mounted upon a suitable support or bracket 70 in turn rigidly secured to the truck frame 11 by bolts 71, or the like.

In use, the flange oiler and oil tank are mounted as shown in Figure 1. By virtue of the slots 19 in the mounting bracket 14, the slide 22 carrying the other elements of the flange oiler

may be adjusted to properly engage different sizes of locomotive wheels. This adjustment can be made without removing the cover plate 56'. The spring 52 maintains the lubricating roller 5 44 in resilient engagement against the wheel flange 12 and allows the roller and bar 29 to move radially with respect to wheel 10, as same passes over track irregularities and the like. Lateral or axial wandering of the wheel 10 is taken care of in two ways. First, the roller 44 has limited axial play upon the shaft 34 as stated. Also, the bar 29 can swing laterally in either direction in the groove 23. This swinging is limited by the diverging sides 24 and 25. The bar 15 29 carrying the roller 44 and associated elements is universally slidably mounted within the groove 23. The spaced openings 57 and 58 are provided so that a pin or the like may be inserted therein when the roller 44 is held in a retracted position and out of contact with the wheel flange 12. Such a pin is passed through one of the holes 57 or 58 and engages the adjacent upper edge of the slide 22.

With the device properly mounted and adjusted and the stop-cock 63 open, oil from the tank 62 passes through the wick 66, due to capillary action and absorption, and drips slowly but constantly into the tube 61, Figure 6. The tank 62 is at sufficient elevation to effect a gravity feed through the tube 61. The oil in tube 61 passes downwardly through the same, through elbow 60, nipple 59 and through the axial port 42. From the port 42, the oil flows through port 43 and into annular groove 48. The oil then enters the radial ports 49 and finally the external annular groove 51. Centrifugal force aids the flow of oil through the ports 49. The oil in the outer groove 51 is deposited directly upon the wheel flange 12, and tends to run down the inner side of the same, Figure 3, when frictional contact with the rail occurs. The flow of oil, of course, can be stopped by closing the stop-cock 63. The roller 44 can be retracted from the wheel flange, as stated. The shaft 34 carrying roller 44 can be mounted upon either side 32 of the head 31.

It is to be understood that the form of the invention herewith shown and described is to be taken as a preferred example of the same, and that various changes in the shape, size and arrangement of parts may be resorted to without departing from the spirit of the invention or the scope of the subjoined claims.

Having thus described the invention, I claim:

55. 1. A wheel flange oiler, comprising a mounting bracket adapted to be secured to a wheel truck frame, a slide secured to the mounting bracket and having a longitudinal groove extending for the entire length of the slide, the groove having 60 corresponding sides which diverge toward opposite ends of the slide, an upstanding element secured to the slide and disposed near the center of the groove, a bar universally slidably mounted within the groove and having a longitudinal slot 65 slidably receiving the element, a spring arranged in the slot and engaging one end of the slot and the element and serving to urge the bar outwardly of one end of the slide, a cover plate mounted upon the slide to cover the groove and enclosing the spring, the bar including a part 70 mounted upon the part for contacting the wheel flange for applying oil to the same.

2. A wheel flange oiler, comprising a mounting bracket adapted to be secured to a wheel truck

frame, a slide secured to the mounting bracket and having a longitudinal groove extending for the entire length of the slide, the groove having corresponding sides which diverge toward opposite ends of the slide, an upstanding element secured to the slide and disposed near the center of the groove, a bar universally slidably mounted within the groove and having a longitudinal slot slidably receiving the element, a spring arranged in the slot and engaging one end of the slot and the element and serving to urge the bar outwardly of one end of the slide, the bar including a part extending beyond one end of the slide, and means mounted upon the part for contacting the wheel flange for applying oil to the same.

3. In a device for oiling the wheel flanges of rail-guided vehicles during the operation thereof, a mounting bracket having a slide with a shaped longitudinal groove said groove defined by corresponding sides diverging outwardly toward opposite ends of the groove, an element upstanding from said slide and disposed within said groove, a slotted bar universally slidably mounted within the groove on said element positioned within the bar slot, one end of said bar protruding beyond said bracket, a lubricating device rotatably mounted upon the protruding end of said bar and adapted to roll a film of oil upon the wheel flange, and spring means positioned between said element and bar for maintaining said lubricating device in resilient engagement with said wheel flange.

4. In a device for oiling the flanges of wheels of rail-guided vehicles during the operation

thereof, the combination of a lubricant applying roller and a resilient mounting device for said roller, said mounting device comprising a mounting bracket adapted to be secured to a wheel truck frame, a slide secured to the mounting bracket and having a longitudinal groove, the groove having corresponding sides which diverge toward opposite ends of the slide, an upstanding element secured to the slide and disposed near the center of the groove, a bar universally slidably mounted within the groove and having a longitudinal slot slidably receiving the element, a spring arranged in the slot and engaging one end of the slot and the element and serving to urge the bar outwardly of one end of the slide, the bar including a part extending beyond one end of the slide and a shaft affixed to said part.
